UNITED STATES PATENT OFFICE.

FITZHUGH TOWNSEND, OF NEW YORK, N. Y., ASSIGNOR TO GENERAL RAILWAY SIGNAL COMPANY, A CORPORATION OF NEW YORK.

SYSTEM OF AUTOMATIC BLOCK-SIGNALING.

1,116,763.

Specification of Letters Patent. Patented Nov. 10, 1914.

Application filed January 26, 1906. Serial No. 297,105.

To all whom it may concern:

Be it known that I, FITZHUGH TOWNSEND, a citizen of the United States, residing at New York city, county and State of New York, have invented a System of Automatic Block-Signaling, of which the following is a specification.

My invention relates to a system of automatic signaling applicable to steam or electric railroads.

In my prior applications, Serial Nos. 281,538 filed October 5th, 1905, and 290,299 filed December 4th, 1905, I have described a system of automatic signaling involving the employment of signal controlling devices normally energized by polyphase currents and deenergized by the movements of a motor vehicle into a block section. In this application I make use of such a signal controlling device, as also various other novel features which serve to improve the system as a whole, such for instance as: (a) A three position relay adapted to control "home" and "distant" signals. (b) An induction device having a movable member adapted to control the relation of the current phases employed to actuate the relay device employed. (c) Signaling devices adapted to indicate the condition of two blocks. (d) A device for preventing the signaling current of one block section from entering an adjacent block section when the insulation of a rail joint is broken.

Figure 1 illustrates my system as embodied in a steam railroad and where the signaling current is derived from a two phase line. Fig. 2 illustrates my system as embodied in a steam railroad, where the signaling current is derived from a single phase line. Fig. 3 illustrates my system as embodied in an electric railway employing one rail as a return for the propulsion current and the signaling current derived from a two phase line. Fig. 4 illustrates my system as embodied in an electric railway employing both rails as a return for the propulsion current and the signaling current derived from a single phase line.

Referring to the diagrams; 5, 6, indicate the track rails. In Fig. 3, the track rail 6 is shown as continuous; in all the other figures, the track rails are shown as divided into block sections, A, B, C, the rails of each section being insulated from corresponding rails of adjacent sections.

S indicates a source of signaling current. In Figs. 1 and 3 this source consists of a two-phase generator of what is known as a three-wire two-phase type; the continuous conductor which is formed of the alternate rails 5, 6, of successive blocks (Fig. 1) or the rail 6 (Fig. 3), being connected to the common point of both phases at source S, carries the resultant return current of the signaling conductors. 65

In Figs. 2 and 4, a single phase source S' is employed.

In each of the four figures a difference of alternating current potential is created across the rails 5, 6, through the instrumentality of a transformer T, having its primary 7 excited from one phase of the signaling current source, and its secondary 8 connected across the trackway.

P indicates a source of propulsion current, which is shown as a direct current generator, although, as is now well understood by electricians, an alternating current generator might be employed without in any wise altering the operation of the system described. 75

R indicates a signal controlling device or relay, which consists of a stator member 9 having two coils 10 and 11. In Fig. 1, the coil 10 is connected across the trackway and the coil 11 across the secondary of a transformer E, whose primary 13 is connected across one phase of the source of signaling current. The coil 11 therefore has a current of definite phase and intensity, while the coil 10 carries a current differing in phase from that of the coil 11, and is adapted to be short circuited by the movements of the car into and out of the block section. 85 90

In Fig. 2 the coils 10 and 11 are both connected across the source of signaling current, but a difference of phase is maintained between the currents traversing these coils by means of the reactance device 14 in series with the coil 10 and a resistance device 15 in series with the coil 11. The rotating field due to the coils 10 and 11 is therefore constant in this modification of my invention. 95

In Fig. 3 the coil 10 is connected across a reactance 16, which is in series with a resistance 17, and such reactance and resistance connected across the rails 5, 6. The coil 11 is connected across a coil 18 wound on a movable member of a phase controller 110

K, which will hereinafter be further described.

In Fig. 4 the coil 10 is connected across the terminals of a reactance bond H, which bond is connected across the rails 5, 6, and the coil 11, as in Fig. 3, is connected across the winding 18 on a movable member of the phase controller K.

The relay R is provided with a rotor member 19. In Figs. 1, 3 and 4 this rotor member consists of a closed circuited coil 20, or as otherwise known, is of the "squirrel-cage" type.

In Fig. 2 the coil 20 is shown as having 15 opposite points of its winding connected across the rails 5, 6. Connected to the rotor member 19 is an arm 21, adapted in Figs. 1, 2 and 4, when turned to the left, to establish contact between it and the contact 20 block 22, and when turned to the right, to establish contact between it and the contact blocks 23, 24.

In Fig. 3, two relays R' and R are shown. The relay R' has an arm 21, adapted when turned to the left to make contact between it and contact block 25, and when turned to the right to make contact between it and contact block 26. The relay R has an arm 21, adapted to make contacts 30 in the same manner as the relay R in the other figures. The relay R' in this figure acts as a master relay controlling the motion of the relay R which carries out the functions fulfilled in the other figures by 35 the relay R alone.

In Fig. 1 the outer end of the arm 21 is connected to one terminal of a short secondary 27, which forms part of the main secondary 12 of transformer E. The opposite 40 terminal of this short secondary 27 is connected to one terminal of a traction magnet coil 28, the opposite terminal of which is connected to the contact blocks 22, 24. Situated in this traction coil is a core 29 45 connected to the upper or "home" signal arm 31. The traction coil 28 will be energized as long as the arm 21 makes contact with either of the contact blocks 22 and 24. This terminal of the short secondary is also 50 connected to one terminal of the traction magnet coil 32, whose other terminal is connected to the contact block 23. The core, 33, of this coil, is connected to the lower or "distant" signal arm 34. The traction coil 55 will therefore only be energized when the arm 21, moving to the right, comes in contact with the contact block 23. As will be understood, the "home" signal of any block section indicates the condition of that block 60 section, and the "distant" signal indicates the condition of the succeeding block section in the direction of traffic. Thus in Block A the "home" signal is shown at "clear" and the "distant" signal at "danger". This indicates that the section A is unoccupied,

while the section B contains a motor vehicle. In section B both arms are shown at "danger", for there is a motor vehicle in section B, and the "home" signal for this section properly goes to "danger". The 70 "distant" signal also goes to "danger", although there is no vehicle in section C. The fact that both signals go to "danger" under conditions shown, however, makes no difference, as with a vehicle in section B, 75 the condition of section C is immaterial. In section C, both signal arms are shown at "clear" indicating that section C, and the succeeding block sections are both unoccupied. Each block section is energized at 80 the right hand end by means of the secondary 8 of a transformer T. The polarity of the supply of signaling current to the block sections is controlled, in Figs. 1, 3 and 4, by means of a reversing switch V. This switch consists of the arms 35, 36, connected to the "home" signal 31 and adapted to 85 contact with the contact blocks 37, 38, 39. In these figures the arms 35, 36, are respectively connected to the terminals of the secondary 90 8 of transformer T. The contact blocks 37, 39, are connected through the conductor 40 to the rail 5 and the contact block 38 through a conductor 41 to the rail 6. It will be understood that when the arms 35, 95 36, cover the contacts 37, 38, one polarity exists, and when the arms 35, 36 cover the contacts 38, 39, the opposite polarity exists.

In Fig. 2 no provision is made for reversing the polarity. The arms 35, 36, co-act 100 with contact blocks 37, 38, when the "home" signal is at "danger" as shown in block B, but do not make contact when the "home" signal is at "clear" as shown in blocks A and C.

In Fig. 1 the transformer T is shown as 105 designed to be of poor regulation and for the purpose of limiting the signaling current when the secondary 8 is short circuited by a motor vehicle.

In Fig. 2 there is a reactance 43 in one leg of the secondary 8 and a variable resistance 44 in the other leg, the purpose of which arrangement is to control the phase of the signaling current supplied to the block 115 sections.

In Figs. 3 and 4 the resistance 44 alone is shown. It will of course be understood 120 that the requirements as to phase control depend upon the condition of the trackway, etc. In Fig. 3 the relay R', through its arm 21^a, is adapted to make contact with contact blocks 25, 26, and the arm 21 of the relay R to make contact with the block 22. The purpose of this arrangement is that 125 only one contact shall be made at a time, thus necessitating less torque in the relay, and consequently less power in the track circuit. The relay R of Fig. 3 has its stator member provided with two coils 50 and 51. 130

The currents for these two coils are furnished from the field coils of the phase controller K, acting as the windings of a polyphase autotransformer. The stator member 5 of the phase controller K consists of two coils 52 and 53. The coil 52 is connected across one phase of the source of signaling current. The coil 53 is connected across the other phase of the source of signaling current. The coil 50 of the relay R is connected at one end to the arm 21^a of the relay R' and at the opposite end to one terminal of the coil 53. The coil 51 is connected across the upper portion of the coil 52 of the phase controller K, thus normally receiving a corresponding portion of the voltage impressed upon said coil 52.

The contact block 25 is connected to a point on the winding of the coil 53 of the phase controller K and the contact block 26 is connected to the terminal of a short coil 54 connected at its opposite end to the coil 53 and wound in opposite direction to the coil 53. The portion of the coil 53 included between its ends and the point where the conductor leading to the contact block 25 is tapped out is of the same length as the coil 54.

When the arm 21^a of the relay R' is in contact with the block 26, the stator coil 50 of relay R will receive a current from the coil 54, whereas when the arm 21^a is in contact with the block 25, the coil 50 will receive an equal and opposite current derived from the coil 53.

In Figs. 1 and 2, I have shown a short conductor 60, introduced between the rail 5 of one block and the opposite rail 6 of an adjacent block and vice versa. The purpose of this arrangement is to provide for short circuiting the signaling current upon itself in a block section in case the insulation between the traffic rails at the segregating points between block sections is by any means destroyed. Instead of using such arrangement, I may use that shown in Figs. 3 and 4.

In Fig. 3 there is shown a short section of rail 70 which is insulated from the adjacent sections of rail 5. The short section 70 is connected to the rail 6 through a conductor 71. In practice, this conducting section 70 may be embodied in the insulating material of what is known as the end post, thus constituting a composite end post.

In Fig. 4 the conducting sections 70 are shown as of different length; short between the sections A and B and long between B and C. In this figure the sections 70 are located in both rails 5 and 6 and are connected through a cross conductor or conductors 71. The only difference between the arrangement shown between blocks A and B, and B and C, is that the factor of safety in the arrangement between B and C

is slightly greater, owing to the fact that the cross conductors 71 are duplicated. The cross conductors 71 are connected through conductors 72 to the central point on the bonds H of adjacent sections. It will be understood that in case of the breaking down of a joint, these short sections 70 and their cross conductor or conductors 71 will serve to short-circuit one-half of the corresponding bond H, thereby lowering the potential across the stator coil 10, destroying the torque on the rotor 19 and thus giving a "danger" signal in the block in which the broken joint occurs.

In Fig. 2 a resistance 80 is shown interposed in the circuit of the coil 20, wound on the rotor member 19 of the relay R. When a motor vehicle enters a block section, the wheels of the vehicle short circuit the resistance 80, as also the impressed signaling current from the transformer T, thus cutting the signaling current out of the coil 20. It will be observed that this is done without affecting the current flowing in the stator coils 10 and 11 of the relay R of this figure.

I will now describe the operation of my system.

In Fig. 1 the alternating difference of potential derived from, for instance, a transformer T in block D (not shown) normally excites the stator coil 10 (Fig. 1) and moves the arm 21 of the relay R to the right, establishing contact between the blocks 23, 24, thereby closing the circuit between the secondary 27 of transformer E and the coils 28, 32, which, through their cores 29, 33, move the signal arms 31, 34, to the "clear" position, as shown in block C. At such time, the arms 35, 36, are in contact with the blocks 37, 38, thereby closing the circuit of the secondary 8 of transformer T of block C through the coil 10 of block B (Fig. 1). Thus, in block C in the absence of a car, both signals are in the "clear" position. When a car enters a block section, as in block C, it short circuits the stator coil 10 and the arm 21 moves to the intermediate position, as shown in block B, and as the arms 31, 34 of the signal are counterweighted, they move to the "danger" position, at which time the arms 35, 36, cover the contact blocks 38, 39, thus reversing the polarity of the signaling current supplied to the preceding block section A. This reversal of polarity causes a reversal of the direction of rotation of the rotor member 19 of the relay R, which causes the arm 21 to make contact with the contact block 22 and closes the circuit between the secondary 27 of transformer E and coil 28, which energizes its coil and attracts its core 29 and holds the signal arm 31 (namely, the "home" signal) in the "clear" position. As the coil 32 at such time is not energized, the signal which

110
115
120
125
130

- indicates "danger" position, remains at "danger." This indicates to a train about to enter block section A from the left, that section B is occupied, while section A is clear.
- 5 The operation of the rotary phase controller K is as follows: The rotor member carries a winding 18, which may be the usual ring armature winding, diametrically opposite points of which are connected to coil 11.
- 10 The phase of the currents which flow in the coil 11, will depend upon the angular position of these opposite connections with relation to the coils 52 and 53, and which can be altered by means of the handle 75. It will
- 15 be understood by electricians that the relay R' operates more efficiently when there is a certain particular phase relation between the currents in the stator coils 10 and 11, and that such a relation can be obtained by varying the position of the controller arm 75, thus varying the phase of the current supplied to the coil 11.

In Fig. 2, the relay coils 10 and 11 are constantly energized from the signal mains connected with the generator S'. Normally, when the track is clear, the rotor coil 20 is in circuit with the resistance 80, through the track rails, and this resistance in the circuit enables the relay field to produce a 30 turning moment or torque in the rotor, causing the arm 21 to turn to the right as shown in block C, and moving both "home" and "distant" signals into "clear" position. When a car moves into the block, as in section B, the resistance 80 is short-circuited, destroying the torque upon the rotor of the relay and causing both signals to assume the "danger" position. In this position the arms 35, 36, of the "home" signal engage 40 the contact blocks 38 and 39, connecting the transformer 8 with the rails of block A, and causing a current to flow through the relay coil 20 of that block of a phase to produce a torque in the reverse direction, thus throwing the arm 21 into engagement with contact block 22, the effect of which is to send the "distant" signal to "danger" as previously explained in connection with Fig. 1.

In Fig. 3, the relay R' is of the three-position type, as shown in the other figures, and when it moves to the right or to the left, the relay R assumes corresponding positions. This is accomplished by the reversal of the current in the coil 50 in the relay R depending upon the position of the relay R'. When the arm 21^a makes contact with the contact plate 25, current flows from the coil 53 through the coil 50, producing in conjunction with the current in coil 51 a turning 50 moment in a clockwise direction of the rotor member of the relay R. When, however, the arm 21^a makes contact with the contact plate 26, current of an opposite polarity flows from the coil 54 on account of the reverse direction of the winding 54 through the coil

50, thus reversing the torque of the relay R and causing the arm 21 to move to the right. When the relay R' is deenergized by the presence of a motor vehicle on the block section, the arm 21^a makes no contact at all and assumes the intermediate position, thus deenergizing coil 50 and causing the arm 21 of the relay R to assume a corresponding position.

Having thus described my invention, I claim:

1. In a signaling system track circuit, two lines of rails, the physical continuity of each line of rails being interrupted at approximately opposite points at intervals forming blocks, an insulating body abutting the rear rail end and an insulating body abutting the forward rail end at such points and a conducting body situated between the two said insulating bodies, signals, sources of signaling current connected to the rails of the blocks, means to utilize the said current to govern the position of said signals at an end of the block, a source of propulsion current, a car, means to convey propulsion current to the car, means forming a return path for propulsion current to the source, comprising both rails of the blocks and bonds connected across the rails of the blocks at both ends and a conductor joining the middle points of adjacent bonds, said bonds being so strongly inductive to the signaling current as to largely prevent its passage, but offering slight resistance to propulsion current, and a conductor connecting each of said conducting bodies to the said conductor joining the middle points of adjacent bonds.

2. In a railway signal system, a trackway composed of conductors formed into a plurality of closed circuited track circuits, means including two insulating bodies abutting the ends of two adjacent conductors of the trackway to isolate the several track circuits, a conducting body interposed between the two insulating bodies, means connected to the conducting body for affording a path of low electrical resistance between the conductors of the trackway upon the formation of a conducting path through the conducting body from one conductor to an adjacent conductor.

3. In a railway signaling system, a trackway composed of conductors formed into a plurality of closed circuited track circuits, means for separating the track circuits interposed between the several track circuits in each of the conductors forming the trackway, each consisting of two insulating bodies abutting the ends of adjacent conductors of the track circuits, an interposed conducting body and a conductor connecting the conducting bodies in opposite lines of rails.

4. In a railway signaling system, track

circuits, a trackway composed of lines of rails, means constantly acting to create a signaling difference of potential between the rails of the trackway, means to utilize 5 said difference of potential to govern a signal, means to divide the trackway into blocks interposed in each line of rails, said last named means consisting of a conducting body and two insulating bodies separated 10 by said conducting body, one of said insulating bodies abutting a rear rail and the other abutting a forward rail of one line of rails, and a conductor attached to said conducting body at one end and attached 15 to the similarly situated conducting body in the other line of rails.

5. In a signaling system for electric railways, a trackway composed of rails, means for separating the trackway into a plurality 20 of closed circuited track circuit sections, consisting each of two insulating

bodies one abutting a rear rail of the trackway the other abutting the adjacent forward rail and a conducting body between them, interposed at opposite points in the lines 25 of rails, a source of propulsion current, a car, means to convey the propulsion current to the car, and means including both rails and a conductor between adjacent track circuit sections forming a return to the source 30 of propulsion current, an electrical connection from the conducting bodies to the conductor between adjacent track circuit sections, signals controlled by said track circuit sections. ³⁵

In testimony whereof, I affix my signature, in the presence of two witnesses.

FITZHUGH TOWNSEND.
